(57) **CLAIM**

The ornamental design for a surgical gas diffuser, as shown and described.

DESCRIPTION

FIG. 1 is a front, right, and bottom perspective view of a first embodiment of a surgical gas diffuser, which embodies our design.

FIG. 2 is a rear, right, and top side perspective view thereof.

FIG. 3 is a front view thereof.

FIG. 4 is a rear view thereof.

FIG. 5 is a right side view thereof.

FIG. 6 is a left side view thereof.

FIG. 7 is a bottom view thereof.

FIG. 8 is a top view thereof.

FIG. 9 is a front, right, and bottom perspective view of a second embodiment of a surgical gas diffuser, which embodies our design.

FIG. 10 is a rear, right, and top side perspective view thereof.

FIG. 11 is a front view thereof.

FIG. 12 is a rear view thereof.

FIG. 13 is a right side view thereof.

FIG. 14 is a left side view thereof.

FIG. 15 is a bottom view thereof; and,

FIG. 16 is a top view thereof.

The broken lines in the drawings illustrate portions of surgical gas diffuser and form no part of the claimed design. The surface shading is an artefact of filing in the United States of America and does not necessarily form part of the
